(57) **CLAIM**

The ornamental design for a helmet for motorcyclists as shown and described.

DESCRIPTION

1. Helmet for motorcyclists

1.1 : Perspective

1.2 : Perspective

1.3 : Front

1.4 : Back

1.5 : Top

1.6 : Bottom

1.7 : Right

1.8 : Left

1.9 : reference view showing the helmet without the visor
The article is used as a helmet for motorcyclists and the
feature of the design is the overall shape of the article which
is best illustrated in the front perspective view in Reproduction
1.1; Reproduction 1.9; Perspective view with the visor
removed for clarity.

The broken lines shown in the reproductions depict portions
of the helmet for motorcyclists that form no part of the
claimed designs.

1 Claim, 9 Drawing Sheets
